UNITED STATES PATENT OFFICE.

JOHN L. OSBORNE, OF ROCHESTER, NEW YORK, ASSIGNOR TO JUDSON GOVERNOR COMPANY, OF ROCHESTER, NEW YORK, A CORPORATION OF NEW YORK.

GOVERNOR FOR COMPRESSORS.

1,136,607.

Specification of Letters Patent.

Patented Apr. 20, 1915.

Application filed May 29, 1913. Serial No. 779,781.

To all whom it may concern:

Be it known that I, JOHN L. OSBORNE, a citizen of the United States, and resident of Rochester, in the county of Monroe and State of New York, have invented certain new and useful Improvements in Governors for Compressors, of which the following is a specification.

This invention relates to improvements in governors of the type employed in connection with engines used to actuate pumps or compressors for charging storage tanks or receivers with air or other fluids.

In governors of the type in question it is customary to employ a centrifugal speed-controlled element, actuated by the engine and a pressure-controlled element actuated by pressure communicated from the storage-tank or receiver, these two elements having a conjoint action upon a throttle-valve or other engine-controlling element, in such a manner as to regulate the speed of the engine, between predetermined limits, in accordance with the variations in pressure in the receiver.

The present invention relates particularly to improvements in the pressure-controlled element of a governor of this type.

One object of the invention is to provide a governor, of the type in question, with a pressure-controlled element so constructed and arranged that it may be conveniently disassembled and reassembled, when necessary, for inspection or repair of its parts.

Another object of the invention is to provide the pressure-controlled element with simple and effective means for controlling the operation of a device, commonly described as an unloader, for throwing the air-pump completely out of operation when the pressure in the receiver exceeds a predetermined degree.

Other objects of the invention, and the features of construction and arrangement by which the several objects are attained, will be set forth hereinafter, in connection with the description of the illustrated embodiment of the invention.

In the accompanying drawings—Figure 1 is a side-elevation of a governor embodying the present invention, together with a throttle-valve controlled thereby, parts of the mechanism being shown in vertical sec-

tion; Fig. 2 is a vertical section, on a larger scale, of the pressure-controlled element of the governor; Fig. 3 is a vertical section on the line 3--3 in Fig. 2; Fig. 4 is a vertical section of the unloader-operating valve, on the line 4--4 in Fig. 2, and Fig. 5 is a partial horizontal section of the governor, showing particularly the pressure-controlled element and the mechanism by which it is connected with the throttle-valve stem and with the speed-controlled element.

In United States Letters Patent granted to me July 16, 1913, No. 1,061,563, I have disclosed a governor of the type in question, and I have illustrated the present invention as embodied in a governor having the same general form and mode of operation as the governor of said patent. The illustrated governor is provided with a speed-controlled element in the form of centrifugal mechanism, this mechanism comprising weights 10 rotatably about a horizontal axis. The centrifugal mechanism is supported and actuated by a horizontal power-shaft 71, which is provided with a bearing 71, through which it may be turned in the usual manner, to the engine to which the compressor is attached. As in said patent, the action of the centrifugal mechanism is communicated to the other parts of the governor through a horizontal sleeve 12, which abuts against the end of a sleeve 13 moved by the weights 10 in the manner clearly indicated in Fig. 1. The forward end of the sleeve 12 is supported by a sleeve 16 at the upper end of a cylinder 18, with the rear portion of the sleeve 12 fitting over an inner sleeve 14, supported on a second column 22. The construction and operation of these parts is or may be substantially similar to that disclosed in my said patent, so that further description is unnecessary, it being understood that the sleeve 12 is moved more or less to the right of the position illustrated in Fig. 1, whenever the centrifugal-mechanism is rotated at a speed exceeding a predetermined degree, this speed corresponding to the speed of the compressor-engine.

The lever-arm 15, which is controlled by the governor, as illustrated in Fig. 1, is of a self-acting rotary type, and it is provided with a vertical valve-stem 16 fixed to a short vertical shaft 68 journaled in a

bracket 49 on a column 13, all as in said patent. To the upper end of the shaft 68 is fixed an arm 17, provided with a bearing-boss 50 which engages one end of a horizontally-disposed lever 18. This lever is pivoted, at its middle, on a pin 19 mounted in a bracket 20 which projects from the bottom of the sleeve 12, so that the fulcrum of the lever 18 moves horizontally with the sleeve. The opposite end of the lever 18 bears against the lower end of a lever 21, which constitutes a part of what is herein-after described as the pressure-controlled element of the governor. A spring-pressed plunger 46, slidably mounted on the arm 17, has a pointed head 47 which bears in a socket 48 integral with the bracket 49. This plunger tends constantly to swing the arm 17, and rotate the throttle-valve 15, in a direction to open the valve, and in this manner the arm 17 and the levers 18 and 21 are maintained constantly in co-operative relation through force-closure. The movements of the arm and of the throttle-valve are controlled, however, by the relative position of the fulcrum 19 and the lever 21. In this manner the throttle-valve is controlled, as in the governor disclosed in my said patent, in accordance with the relative positions of the sleeve 12, as determined by the centrifugal mechanism, and of the pressure-controlled element, as determined by the pressure in the receiver.

The pressure-controlled element, in which the present invention particularly resides, comprises a cylinder 23, which is mounted in vertical position upon the column 22, the cylinder being provided, for this purpose, with a lug 25 which is engaged by a screw 24 passing through the column, as shown in Fig. 5. The connections between the pressure-controlled element and the lever 18, by the mere engagement of the ends of the levers 18 and 21, is such as to permit the pressure-controlled element to be readily detached from the rest of the governor, when desired, by merely removing the screw 24.

Integral with the cylinder 23 is a bracket 26, provided with a horizontal pivot-pin 27 upon which the lever 21 is mounted, the bracket 26 constituting also the support for certain other parts of the mechanism of the pressure-controlled element, as hereinafter described.

Within the lower part of the cylinder 23 a piston 29 is inclosed, this piston having a substantially air-tight fit in the cylinder but being freely movable therein. This piston is actuated by compressed fluid from the receiver, the fluid being admitted to the lower end of the cylinder through an inlet, shown in Fig. 3, which is connected with the receiver by a fitting 35 and a pipe 36. The upper end of the piston is provided with a bifurcated projection 30, of which

the middle-portion is engaged by one arm 31 of a bell-crank lever mounted on a pivot-pin 32 in the bracket 26. The other arm 33 of the bell-crank lever is provided with a roller 34, which engages the lever 21 between its pivot 27 and its lower end, as shown in Fig. 2. This arrangement is such that when the piston 29 rises in the cylinder 23 the bell-crank lever is rocked in a direction to swing the lever 21 outwardly, or to the left as shown in Fig. 2, the movement being multiplied by the action of the levers. In this manner the movements of the piston, due to variations in the pressure in the receiver, are communicated, through the various levers, to the throttle-valve, so as to vary the speed of the engine accordingly.

To counterbalance the pressure against the piston 29 I employ, as in the governor of my said patent, a spring of which the force may be adjusted in accordance with the pressure which it is desired to maintain in the receiver. In the present construction, however, this spring is arranged to act upon the piston without the intermediation of the mechanism by which the piston is connected with the other parts of the governor. The upper part of the cylinder 23 provides a housing for this spring, and the spring is coiled about a tubular guide 38. This guide is provided, at its lower end, with a plug 39 which slides freely within the cylinder, and which affords a seat for the lower end of the spring. At the middle of the lower surface of the plug is a pointed pivot 40, which rests in a recess in a plate 41, which also slides freely in the cylinder. The downward movement of the plate is limited by a shoulder 42 on the inner surface of the cylinder.

The upper end of the spring 37 bears against a screw-threaded sleeve 43, which is screwed into the upper end of the cylinder 23 and is locked in place by a lock-nut 44. The spring-guide 38 slides freely through the upper end of the sleeve 43, but is provided with a flanged plug 45 at its upper end, which limits the downward movement of the guide with respect to the sleeve.

When the piston 29 is at its lowermost position in the cylinder 23 the plate 41 rests upon the shoulder 42; but as soon as the piston begins to move upwardly the upper extremities of the bifurcated projection 30 engage the lower surface of the plate, so as to raise the plate and the spring-guide and increase the compression of the spring. The pivotal connection between the plug 39 and the plate 41 causes the plate to bear evenly upon the projection 30, without any tendency to cause lateral pressure between the piston and the cylinder. It has the further advantage that when the sleeve 43 is turned to screw it into or out of the cylinder, and thus regulate the compression of the spring,

the plug 39 can turn upon the plate 41, thus facilitating this adjustment and preventing the subjection of the spring to torsion.

The sleeve 43 is rotated, as above described, to adjust the pressure of the spring 37 against the piston, in accordance with the pressure which is to be maintained in the receiver.

The arrangement of the connecting-levers 10 and the spring-mechanism just described greatly facilitates the assembling and disassembling of the parts of the pressure-controlled element, particularly by reason of the fact that the spring acts upon the 15 piston independently of the lever-mechanism. When it is desired to remove the piston from the cylinder this may be readily done, for the reason that the piston, when in its lowermost position, is not subjected 20 to any pressure from the spring. Accordingly, upon the removal of the cap 28 the piston may be withdrawn, while the spring remains in its usual condition, being supported by the spring-guide, and by the engagement of the plate 41 with the shoulder 42. At the same time no operation is required to disconnect the piston from the bell-crank lever, owing to the fact that the lever is merely in free engagement with the 30 projection 30 of the piston. If it be desired, on the other hand, to remove the spring 37 from the cylinder 23, this can be readily done since the pivotal connection between the spring-guide and the plate 41 35 facilitates the unscrewing of the sleeve 43, as above described, and when the sleeve has been unscrewed sufficiently to engage the flange 45 at the upper end of the spring-guide, which occurs before the lower end of 40 the sleeve has been unscrewed from the cylinder 23, the pressure of the spring is sustained by the spring-guide, so that there is no tendency to force the sleeve 43 violently from the upper end of the cylinder when 45 it becomes entirely unscrewed therefrom. The sleeve, the spring, and the spring-guide may then be removed from the cylinder, and they remain in co-operative position ready to be replaced.

50 As a simple and convenient means for regulating the maximum and minimum speeds of the engine, I employ two stop-screws 51 and 52, which are threaded into the bracket 26, as shown in Fig. 2, in such 55 a position that their lower ends may be engaged by two lugs 53 and 54 on the lever 21. When the lever swings to the right, in consequence of the descent of the piston 29 corresponding to a diminution of pressure 60 in the receiver, the speed of the engine is accelerated, but when this acceleration has reached a predetermined maximum the lug 53 engages the screw 51, thus preventing further movement of the lever 21 in a direction to accelerate the engine-speed. On

the other hand, the rise of the piston and the corresponding left-hand movement of the lever 21 is limited by the engagement of the lug 54 with the screw 52, so that a minimum speed of movement may be maintained in the engine, notwithstanding the attainment of the predetermined degree of pressure in the receiver, this feature of operation being necessary in the case of a single acting compressor.

The automatic means for controlling the unloader are shown particularly in Figs. 3, 4 and 5 of the drawings. The fitting 35, through which the compressed fluid is admitted, from the pipe 36, to the cylinder 23, is integral with an upwardly-extending casing 55. This casing has a smooth cylindrical bore in which is mounted a rod 56, the rod being fitted closely but freely in the cylinder, so that it may act in the manner of a piston, as hereinafter described. The communication between the fluid-passage in the part 35, and the casing 55, is afforded through an inlet-opening 57, while an outlet-passage 58 leads to a pipe 59, which may be extended from the valve-casing to the unloading-devices of the compressor. These unloading-devices may be of any ordinary or suitable form in which fluid-pressure is utilized to throw the compressor-pump out of operation, and as such devices are well known they are not illustrated or described herein, it being understood that whenever compressed fluid is admitted to the pipe 59 the unloader or unloaders act to throw the pump out of operation, so as to permit it to be moved idly by the engine, which is thus substantially relieved from load.

The lower end of the rod 56 is reduced in diameter and pointed, thus producing a needle-valve 73 which is seated in the inlet-opening 57 and normally closes this opening. In addition to the inlet and the outlet just described the valve-casing 55 is provided, as shown in Fig. 4, with a plug 60 having a minute central orifice which constitutes another outlet or relief-vent from the valve-casing, through which compressed fluid may leak constantly when the casing 115 is filled. When the unloader-controlling valve 73 is opened to admit fluid to the unloader, the flow through the inlet 57 is so much greater than the escape through the relief-vent that the operation of the unloader is not interfered with, but as soon as the controlling-valve is reseated the relief-vent permits the fluid to escape, and the pressure to fall, so rapidly that the unloader is relieved and thrown out of operation almost immediately upon the closing 120 of the controlling-valve, and in this manner the necessity of an exhaust-valve is avoided.

The controlling-valve 73 is normally held to its seat by means of a spring 61 which is 125

coiled around the rod 56, with its lower end in engagement with a flange 62 on the rod. The upper end of the spring is seated against a cap 63, which is screwed upon the upper end of the casing 55, and the pressure of the spring may be adjusted by screwing the cap up or down. The controlling-valve is actuated by connections with the piston 29. To this end nuts 64 are screwed upon the 10 threaded upper end of the rod 56, while an arm 65 is screwed into the upward projection 30 on the piston, and projects horizontally through a vertical slot 66 in the side of the cylinder 23, as shown in Figs. 3 and 5. The 15 arm 65 has, at its outer end, a forked extremity 67 which embraces the rod 56 below the nuts 64, and which is adapted, when the piston 29 is near the upper end of its range of movement, to engage the nuts and raise 20 the rod 56, thus lifting the controlling-valve 73 from its seat.

In addition to its essential function as a device for admitting fluid to the unloader, when the consumption of fluid from the receiver is interrupted and the pressure in the receiver rises to a predetermined degree, the controlling-valve and the associated parts above described coöperate, in a novel manner, with the other parts of the governor to 25 control the movement of the compressor-engine. I have found in practice that it is desirable to utilize the centrifugal element of the governor only for the purpose of controlling the engine-speed at or near the predetermined maximum, while at the lower engine speeds, corresponding to lower rates of consumption of the compressed fluid, the engine-speed is permitted to vary in accordance with fluctuations in the receiver pressure, or in the resistance to which the movement of the engine is subjected by the compressor-pump, under the sole control of the pressure-controlled element of the governor. In the illustrated governor this is accomplished by employing, in connection with the 30 centrifugal element, a coiled spring 74 which resists the movement of the sleeve 69 under the influence of the governor-weights 10, thus holding the weights in their normal inner position until the compressor-engine reaches a speed near its predetermined maximum. Accordingly, when the engine is operating at a low speed, under the control of the pressure-controlled element, and is then 35 suddenly unloaded by the action of the unloader-controlling valve, it will tend to accelerate its speed immediately upon being so unloaded, unless provision against this is made independently of the centrifugal mechanism. This tendency is provided for and controlled, however, by the pressure-controlled element of the present governor. During the normal fluctuations in the pressure of the compressed fluid, below the normal predetermined maximum pressure, the

piston 29 rises and falls under the counterbalanced action of the fluid-pressure and the spring 37, without causing the unloader to operate. The nuts 64 on the rod 56 are so adjusted, however, that when the fluid-pressure reaches this predetermined degree the nuts are engaged by the part 67. The resistance of the spring 61 is then added to that of the spring 37, to oppose further rising movement of the piston 29. The movement of the piston is thus momentarily arrested, and the governor is preferably so arranged that at this moment the engine shall be operating at the lowest speed at which, in the case of a single-acting compressor, its continued rotation can be insured according to the weight of the fly-wheel with which the engine is provided, thus providing for a minimum consumption of steam or other motive-fluid when the consumption of compressed fluid is at a minimum or has ceased. The continued operation of the engine, however, causes a continued increase in the pressure of the compressed fluid, so that presently the pressure, acting through the piston 29, is sufficient to overcome the spring 61 as well as the spring 37, and the rod 56 is then lifted, thus raising the valve 73 from its seat and admitting compressed fluid, through the inlet 57, to the valve-casing 55, and thence, 40 through the pipe 59, to the unloader, which immediately throws the pump out of operation and unloads the engine. This admission of compressed fluid to the valve-casing 55 causes the rod 56 to act as a piston, since the fluid tends to force the rod upwardly out of the cylindrical casing in which, as before stated, it forms a substantially fluid-tight fit. The diameter of the rod and the force of the spring 61 are so selected and adjusted, in accordance with the predetermined pressure of the compressed fluid, that this piston-like effect is sufficient to almost overbalance the pressure of the spring 61. Accordingly, the piston 29 is suddenly relieved of a part of 45 the counterbalancing force, and it immediately rises further in the cylinder 23, thus acting, through the lever-connections of the governor, to further close the throttle-valve 15. By a suitable adjustment of the minimum-speed stop-screw 52, the length of this movement may be so determined that the effect upon the throttle-valve is just sufficient to throttle down the engine to the minimum permissible speed at which the engine can 50 run when unloaded, thus preventing any unnecessary consumption of motive-fluid in the engine, while at the same time preventing the engine from coming entirely to rest.

After the unloader has operated and the engine-speed has been reduced to a minimum, as above described, the piston 29 will not fall again, sufficiently to cause the controlling-valve 73 to close, until an appreciable drop in pressure has occurred in the

compressed fluid, owing to the fact, as above stated, that the pressure at which the controlling-valve is first raised is more than sufficient to maintain the piston 29 in its uppermost position, after the piston has been substantially relieved from the effect of the spring 61 by the piston-like action of the rod 56. Accordingly, the compressor will be held unloaded for a substantial interval of time, provided there is no consumption of the compressed fluid, until the pressure in the receiver has been sufficiently reduced, by leakage, to permit the springs 37 and 61 to force the piston 29 and the rod 56 down wardly, and seat the valve 38. During the descent of these parts, however, the governor-mechanism is moved in a direction to reopen the throttle-valve 41, so that the speed of the engine is maintained and at the instant when the controlling-valve 73 is finally closed and the unloader is thrown out of operation, the throttle-valve is in the same position which it occupied when the engine was previously unloaded. Owing to this arrangement, sufficient speed and power in the engine, to assume the load again, is automatically insured, and the danger of the engine being stopped when suddenly reloaded is avoided.

It will be apparent from the foregoing description that the springs 37 and 61, and the rod 56 acting as a piston, constitute, together, counterbalancing means by which the movements of the piston 29 are controlled when the fluid-pressure at which the compressor is unloaded and the lower pressure at which it is reloaded, is a valuable feature of the operation of the governor, for the reason that it prevents the throttle-valve from being actuated, and the unloader from being thrown into and out of operation, with every slight fluctuation in fluid pressure, thus avoiding the too-frequent operation of these parts, which would cause undue wear in the governor. At the same time the unloader is so controlled as to minimize the consumption of motive-fluid in the compressor-engine, and avoid the necessity of permitting compressed fluid to escape from the relief-valve with which the receiver is usually provided.

An unloader is particularly useful in connection with a compressor of what is commonly designated as the "single-acting" type, that is to say, a compressor in which the engine is so constructed that it may come to rest in a dead-center position from which it cannot start itself. In connection with compressors of other types the unloader is not generally used, and where my improved governor is used in connection with such a compressor the controlling-mechanism for

the unloader may be detached from the other parts of the pressure-controlled element. For this purpose the valve-casing 55 and the fitting 35 are merely unscrewed from the cylinder 23, and the arm 65 is unscrewed from the piston. Accordingly, the governor may be furnished either with or without these parts, without any alteration in its essential elements.

My invention is not limited to the embodiment thereof hereinbefore described and illustrated in the accompanying drawings, but may be embodied in various other forms within the nature of the invention as it is defined in the following claims.

I claim:

1. In a compressor-governor, a pressure-controlled element having, in combination, a cylinder; a piston loosely mounted therein; means for admitting fluid to the cylinder behind the piston; means, for operatively connecting the piston with the valve controlled thereby, comprising a lever having an arm extending in front of the piston and loosely engaged thereby; and a spring-pressed counterbalancing-member independent of said means and also loosely engaged by the piston.

2. In a compressor-governor, a pressure-controlled element having, in combination, a cylinder; a piston loosely mounted therein; a removable closure for the end of the cylinder at the rear of the piston; means for admitting fluid to said end of the cylinder; means, for operatively connecting the piston with the valve controlled thereby, comprising a lever having an arm extending in front of the piston and loosely engaged thereby; and a spring-pressed counterbalancing-member independent of said means but located in front of the piston and loosely engaged thereby.

3. In a compressor-governor, a pressure-controlled element having, in combination, a cylinder; a piston loosely mounted therein; a removable closure for the end of the cylinder at the rear of the piston; means for admitting fluid to said end of the cylinder; means, for operatively connecting the piston with the valve controlled thereby, comprising a lever having an arm extending in front of the piston and loosely engaged thereby; a spring-pressed counterbalancing-member independent of said means but located in front of the piston and loosely engaged thereby; and means for limiting the movement of the counterbalancing-member when the piston is withdrawn from engagement therewith.

4. In a compressor-governor, a pressure-controlled element having, in combination, a cylinder; a piston loosely mounted therein; a removable closure for the end of the cylinder at the rear of the piston; means for admitting fluid to said end of the cylinder;

- means for operatively connecting the piston with the valve controlled thereby, comprising a lever having an arm extending in front of the piston and loosely engaged thereby; and a spring-pressed counterbalancing-member independent of said means but located in front of the piston and loosely engaged thereby, the cylinder and the counterbalancing-member having coöperating abutments 5 to limit the movement of the latter when the piston is withdrawn therefrom.
5. In a compressor-governor, a pressure-controlled element having, in combination, a cylinder provided, at both ends, with removable closures; a piston movable within the cylinder near one end thereof; means for admitting fluid to said end of the cylinder; a counterbalancing-spring inclosed within the cylinder near the other end thereof; and means for connecting the piston with the valve controlled thereby, said means comprising a lever extending transversely into the cylinder and engaging the end of the piston which is adjacent said spring.
6. In a compressor-governor, a pressure-controlled element having, in combination, a cylinder provided, at both ends, with removable closures; a piston movable within the cylinder near one end thereof; means for admitting fluid to said end of the cylinder; a counterbalancing-spring inclosed within the cylinder near the other end thereof; means, for connecting the piston with the valve controlled thereby, said means comprising a lever extending transversely into the cylinder and engaging the end of the piston which is adjacent said spring; and a member engaged by the spring and adapted to be engaged by the piston to transmit the force of the spring to the piston, said member and the cylinder having coöperating abutments to limit the movement of said member under the influence of the spring.
7. In a compressor-governor, a pressure-controlled element having, in combination, a cylinder; a piston movable within the cylinder near one end thereof; means for admitting fluid to said end of the cylinder; a coiled compression-spring inclosed within the cylinder near the other end thereof; a spring-follower engaged by the spring; an intermediate member having a central pivotal connection with the spring-follower and adapted to be engaged by one end of the piston; means for connecting the piston with the valve controlled thereby, and a rotatable member having threaded connections with the cylinder and engaging the end of the spring to adjust the compression thereof.
8. In a compressor-governor, a pressure-controlled element having, in combination, a cylinder; a piston movable within the cylinder, near one end thereof, the cylinder having an inlet-opening for fluid at said 65 end and the piston having a bifurcated pro-
- jection at its opposite end; a spring-pressed counterbalancing-member movable within the cylinder, near the other end thereof, and coöperating with said projection; and means for connecting the piston with the valve controlled thereby, said means comprising a lever pivotally connected with the cylinder and having an arm projecting transversely into the cylinder and engaging the piston between the bifurcations of said projection.
9. In a compressor-governor, a pressure-controlled element having, in combination, a cylinder provided, at one end, with an inlet for the admission of fluid; a piston movable in the cylinder near said end; a counterbalancing-spring inclosed within the cylinder near the other end thereof; an adjusting-sleeve engaging one end of the spring, and having a screw-threaded connection with the cylinder whereby the sleeve may be moved to adjust the compression of the spring; connections, between the piston and the spring, including a guide engaged by the opposite end of the spring and movable longitudinally through the end of said sleeve, said guide being loosely engaged by the piston and having an abutment adapted to be engaged by the sleeve to limit the expansion of the spring when the sleeve is unscrewed from the cylinder, and means, independent of said guide, for connecting the piston with the valve controlled thereby.
10. In a compressor-governor, the combination of an unloader-controlling device, and means operating automatically, when said device throws the unloader into operation, to effect a simultaneous and substantial reduction in the supply of motive-fluid to the compressor-engine.
11. In a compressor-governor, the combination of a member subject to, and movable in accordance with, the pressure of the compressed fluid; means for connecting said member with a governing-valve; an unloader-controller, connections between said controller and said member whereby the controller is actuated, to throw the unloader into operation, when said member reaches a predetermined position in consequence of the rise in pressure of the compressed fluid; and yielding means, connected with said member, for counterbalancing the pressure against it, said means being adapted to subject said member to a resistance which is substantially reduced coincidently with the operative movement of the unloader-controller.
12. In a compressor-governor, the combination of a member subjected to, and movable in accordance with, the pressure of the compressed fluid; means for connecting said member with a governing-valve; an unloader-controlling valve; connections, between the latter valve and said member, whereby the valve may be moved to operate

- the unloader when said member reaches a predetermined position in consequence of the rise in pressure of the compressed fluid; and means, for opposing the combined action of said member and said controlling-valve, adapted to produce a resistance to movement of said member which is substantially reduced coincidently with the operative movement of the controlling-valve.
13. In a compressor-governor, the combination of a member subjected to, and movable in accordance with, the pressure of the compressed fluid; means for connecting said member with a governing-valve; an unloader-controlling valve; connections, between the latter valve and said member, whereby the valve may be moved to operate the unloader when said member reaches a predetermined position in consequence of the rise in pressure of the compressed fluid; and means, for opposing the combined action of said member and said controlling-valve, adapted to produce a resistance to movement of said member which is substantially reduced coincidently with the operative movement of the controlling-valve and substantially increased coincidently with its return to normal inoperative position.
14. In a compressor-governor, the combination, with a throttle-valve, of centrifugal means for controlling the throttle-valve at the higher speeds of the compressor-engine; and pressure-controlled means for controlling the throttle-valve at the lower engine-speeds, the pressure controlled means including an unloader-controller and being adapted, upon the excess of a predetermined pressure in the compressed fluid, to actuate the unloader-controller and thereby cause the engine to be unloaded, and to simultaneously impart a sudden and substantial closing movement to the throttle-valve to compensate for the unloading of the engine.
15. In a compressor-governor, the combination, with a member subject to, and movable in accordance with, the pressure of the compressed fluid, and means for connecting said member with a governing-valve, of a pneumatic duct for conducting compressed fluid to an unloader; a controller-valve for controlling the admission of fluid to said duct; connections between said valve and said member whereby the valve may be opened by the movement of said member upon the excess of a predetermined pressure in the compressed fluid; counterbalancing-means resisting such movement and holding the controller-valve normally closed; and a piston subject to the pressure in said duct and connected with the controller-valve, said piston acting in opposition to the counterbalancing-means when fluid is admitted to said duct by the opening of the controller-valve.
16. In a compressor-governor, the combination, with a member subject to, and movable in accordance with, the pressure of the compressed fluid, and means for connecting said member with a governing-valve, of a pneumatic duct for conducting compressed fluid to an unloader; a controller-valve for controlling the admission of fluid to said duct; connections between said valve and said member whereby the valve may be opened by the movement of said member upon the excess of a predetermined pressure in the compressed fluid; counterbalancing means resisting such movement and holding the controller-valve normally closed; and a piston subject to the pressure in said duct and connected with the controller-valve, said piston acting in opposition to the counterbalancing means when fluid is admitted to said duct by the opening of the controller-valve, and said duct having an opening through which the compressed fluid may escape when the controller-valve is closed.
17. In a compressor-governor, a pressure-controlled element having, in combination, a cylinder provided with an inlet for fluid and with a lateral opening; a piston movable within the cylinder; an arm projecting, from the piston, through said lateral opening in the cylinder; an unloader-valve casing, alongside the cylinder, having an outlet and having an inlet connected with the inlet of the cylinder; and a spring-pressed unloader-valve normally closing the inlet in the valve-casing and having an abutment adapted to be engaged by said arm to open the unloader-valve in consequence of the movement of the piston in the cylinder.
18. In a compressor-governor, a pressure-controlled element having, in combination, a cylinder provided with an inlet for fluid and with a lateral opening; a piston movable within the cylinder; an arm projecting, from the piston, through said lateral opening in the cylinder; an unloader-valve casing, alongside the cylinder, having an outlet and having an inlet connected with the inlet of the cylinder; and a spring-pressed unloader-valve normally closing the inlet in the valve-casing and having an abutment adapted to be engaged by said arm to open the unloader-valve in consequence of the movement of the piston in the cylinder, the valve-casing having also a minute constantly-open escape-vent connected with the outlet from the valve-casing.
19. In a compressor-governor, a pressure-controlled element having, in combination, a cylinder provided with an inlet for fluid and with a lateral opening; a piston movable in the cylinder; a valve-casing, alongside the cylinder, provided with an outlet and with an inlet communicating with the inlet to the cylinder; an unloader-valve controlling the inlet to the valve-casing; and an arm pro-

jecting from the piston, through said lateral opening in the cylinder, and adapted to coöperate with the unloader-valve to move the latter in accordance with the movement 5 of the piston within the cylinder.

20. In a compressor-governor, a pressure-controlled element having, in combination, a cylinder provided with an inlet for fluid and with a lateral opening; a piston movable in 10 the cylinder; a valve-casing, alongside the cylinder, provided with an outlet and with an inlet communicating with the inlet to the cylinder; an unloader-valve controlling the inlet to the valve-casing; and an arm 15 projecting, from the piston, through said lateral opening in the cylinder and adapted to coöperate with the unloader-valve to move the latter in accordance with the movement of the piston within the cylinder, 20 the valve-casing and the arm being removable from the cylinder and the piston respectively.

21. In a compressor-governor, a pressure-controlled element having, in combination, a 25 cylinder provided, at one end, with an inlet for fluid and with a removable closure; a piston movable within the cylinder near said end; a valve-casing, alongside the cylinder, provided with an outlet and with an inlet connected with the inlet to the cylinder; an unloader-valve, in the valve-casing, controlling the inlet thereto, and an arm, 30 removably mounted in the piston, projecting through said lateral opening in the cylinder, and coöperating with the unloader-

valve to control the valve in accordance with the movements of the piston, the piston being removable through the end of the cylinder when said arm and said closure are removed from the piston and the cylinder, respectively. 40

22. In a compressor-governor, the combination of a motive-fluid valve, a pressure-controlled element, and means actuated by said element and adapted, as the pressure of 45 the compressed fluid rises toward a predetermined maximum, to move said valve gradually toward closed position, and to simultaneously unload the compressor and impart a definite and more rapid closing 50 movement to said valve when the pressure of the compressed fluid reaches said maximum.

23. In a compressor-governor, the combination of an unloader-controlling valve, a 55 motive-fluid valve, a pressure controlled element, and means actuated by said element and adapted to close the motive-fluid valve gradually as the pressure of the compressed fluid rises toward a predetermined 60 maximum, and to impart a definite and more rapid closing movement to the motive-fluid valve, and at the same time open the unloader-controlling valve, when the pressure of the compressed fluid reaches a pre- 65 determined maximum.
